ICE CRUSHER ATTACHMENT

Walter E. Moore, St. Louis, Mo., assignor to Knapp-
Monarch Company, St. Louis, Mo., a corporation of
Delaware

Application March 2, 1959, Serial No. 54,792

Term of patent 14 years

(Cl. D89—1)

Fig. 1 is a perspective view of an ice crusher attachment showing my new design, a mixer base being shown in broken line for illustrative purposes;

Fig. 2 is a top plan view;

Fig. 3 is a front elevational view;

Fig. 4 is a right side elevational view;

Fig. 5 is a rear elevational view; and

Fig. 6 is a bottom plan view.

I claim:

The ornamental design for the ice crusher attachment, substantially as shown and described.
